A. W. LISSAUER

HEAT EXCHANGER

Filed March 31, 1927

UNITED STATES PATENT OFFICE.

ADOLPH W. LISSAUER, OF LOUISVILLE, KENTUCKY, ASSIGNOR TO LOUISVILLE DRYING MACHINERY CO., INC., OF LOUISVILLE, KENTUCKY, A CORPORATION OF KENTUCKY.

HEAT EXCHANGER.

Application filed March 31, 1927. Serial No. 179,754.

My invention relates to a return current indirect heat exchanger of the rotary type in which the greater heat is applied in the inner part of the exchanger.

5 The object of the invention is to provide a more rugged heat exchanger of higher efficiency and economical in upkeep.

In the appended drawing Figure 1 is a longitudinal section of a heat exchanger embodying my invention. Figure 2 is a cross section on line 2—2, Figure 1 and Figure 3 is a similar section on line 3—3 Figure 1.

10 Referring to the drawing, 5 is a furnace preferably of the oil burning type in which the air necessary for combustion is pre-heated by by-passing it through a chamber 6 formed by the refractory lining 7 and the outer shell 8 of the furnace. In addition, 20 the furnace has an air inlet 9 in proximity to the inner central shell 10 of the heat exchanger, the inner shell being in direct communication with the furnace 5. A suitable air seal is preferably provided at the junction 11 of the inner shell 10 with the furnace 5. Co-axial with the inner shell is an outer shell 12 rigidly secured thereto by suitable stays or bolts 13 provided at suitable intervals and preferably extending radially. 25 Tie-rods 14 are also provided between the outer and inner shell near the furnace end of the heat exchanger.

The inner shell at the end remote from the furnace is closed and thereat it is provided 30 with tubes 15 which project through the outer shell 12 and lead into the stationary outer casing 16. The casing with the outer shell 12 forms an annular chamber 17 into which products of combustion enter from the furnace passing through the inner shell 10 and the tubes 15.

The annular chamber 17 has an outlet 18, leading to a low pressure induced draft fan 19. This outlet 18 is remote from where 40 tubes 15 enter the annular chamber.

To increase the path of travel of the products of combustion in the annular chamber, the outer shell 12 is provided with a series of flights or paddles 20, which are secured to the outer shell 12. These paddles are made 50 to subdivide the annular chamber into segmental compartments which force the gases entrapped therein from passing directly into

the fan until said segmental sections are in communication with the outlet 18. By this means I am enabled to maintain a longer contact between the gas of combustion and the outer shell and thereby absorb a greater quantity of heat from such gases than if no paddles are provided in the annular chamber.

At the feeding end of the heat exchanger a suitable feed spout 21 is provided through which the material to be dried is charged into the annular space formed by the inner and outer shells. At the feeding end the annular space enters into a stationary housing 22 which leads into the intake of a high pressure exhaust fan 23. This type of fan creates a slight vacuum in the annular space 70 between the inner and outer shells 10 and 12 respectively. The outer shell 12 and the inner shell 10 at the juncture of same with the housing 22 are provided with air seals 24, and the feed hopper 21 is also provided 75 with air sealing means to prevent air in leakage.

At the feeding hopper, the shell 12 is provided with staggered flights or paddles 25 to facilitate the feed of the material toward 80 the discharge end of the heat exchanger. These paddles are perfectly disposed helically to increase the normal pitch of the dryer at the feeding end for the material.

In addition to the flights 25, a series of 85 staggered flights 26 are provided on the inner surface of the shell 12 which run longitudinally. Cooperating with the flights 25 and 26 of the shell 12 are flights 27 provided on the outer surface of the inner shell 90 10, also running longitudinally. All these flights in addition to stirring the material during its travel through the annular space of the inner and outer shells 10 and 12 respectively, strengthen the two shells and 95 prevent their tendency to buckle under the action of the heat. The shell 12 at the discharge end is provided with suitable means for directing the material to the central outlet 28 which leads into a conveyor 29. The 100 junction of the outlet 28 and the conveyor are provided with a suitable seal 30 to prevent air in leakage.

It may be remarked that the air seals are only used in conjunction with a high pressure exhaust fan 23 when a dustless type of

a heat exchanger is desired. In an ordinary type of heat exchanger, the air seals are eliminated and a low pressure exhaust fan is used which will necessarily draw air into the annular space formed by the shells 10 and 12 and which air would absorb the vapors due to the application of heat to the material to be dried; but essentially the structure of the heat exchanger will be the same with the exception of the type of the fan used and the air seals in connection therewith.

The outer shell 12 may be supported on suitable rolls so that it could be rotated in any suitable way not illustrated. By making the central shell 10 carry the hottest gases, the same can be made of heavier material and being in diameter smaller than the outer shell, it will have a greater resistance to buckling than would the outer shell if it were directly subject to the hottest gases as is common in these types of exchangers.

In subjecting the outer shell 12 to cooler gases, its tendency to buckle is reduced and therefore the same can be made of lighter material. Furthermore, the stays 13 reinforce the two shells and thereby still further decrease the tendency of the two shells to buckle under the heat and weight.

Due to the fact that the hottest gases are passing through the inner shell first, the losses by radiation are greatly reduced. By trapping the gases in segmental chambers while travelling on the outside of the outer shell, a longer contact of the hot gases with the exchanger results. In consequence, a more efficient drying is obtained with the type of heat exchanger described.

I claim:

1. In a heat exchanger, a shell mounted to rotate, a stationary casing about the shell forming therewith an annular chamber, means for supplying products of combustion to said annular chamber, flights carried by the shell and disposed in the annular chamber for controlling the flow of products of combustion therethrough, and means for removing the products of combustion from between the flights at a predetermined place of the annular chamber.

2. In a heat exchanger, a shell mounted to rotate, a stationary casing about the shell forming therewith an annular chamber, longitudinal flights carried by the shell in the annular chamber, means for supplying the annular chamber with products of combustion, and means for removing the products

of combustion from between the flights successively at a predetermined place of the 60 annular chamber.

3. In a heat exchanger, a shell mounted to rotate, a stationary casing about the shell forming therewith an annular chamber, means carried by the shell and dividing the 65 annular chamber into a plurality of longitudinal sections, means for supplying products of combustion to the sections of the annular chamber, and means for removing the products of combustion from the 70 sections successively.

4. In a heat exchanger, a rotary and a stationary part forming an annular chamber adapted to receive products of combustion, means dividing the chamber into a plurality 75 of longitudinal sections, and means for removing the products of combustion from the sections of the annular chamber successively as the rotary part revolves.

5. In a heat exchanger, a stationary and 80 a rotary part forming an annular chamber adapted to receive products of combustion, movable flights in said chamber dividing the same into a plurality of longitudinal sections, and means associated with the stationary part for removing the products of combustion from said sections successively. 85

6. In a heat exchanger, a stationary and a rotary part forming an annular chamber adapted to receive products of combustion, 90 longitudinal flights in said chamber dividing the same into sections and means associated with the stationary part forming a chamber for removing the products of combustion from the chamber and adapted to register 95 with the section of the chamber as the rotary part revolves.

7. In a heat exchanger, a stationary and a rotary part forming an outer annular chamber, said rotary part having an annular 100 chamber which is surrounded by the outer chamber and therefore forms an inner annular chamber, means for supplying products of combustion to the outside of the inner periphery of the inner annular chamber, means for conveying the products of combustion to the outer annular chamber, means for removing the products of combustion from the outer annular chamber, and means in said outer chamber dividing the same into a plurality of longitudinal sections, each adapted to register with the means for removing the products of combustion as the rotary part mentioned revolves. 105 110

ADOLPH W. LISSAUER.
